United States Patent Office

Des. 193,163
Patented July 3, 1962

193,163

HIBACHI OR SIMILAR ARTICLE

Ralph Levi, New Rochelle, N.Y., assignor to Imperial International Corp., New York, N.Y., a corporation of New York

Filed Mar. 29, 1961, Ser. No. 64,531

Term of patent 3½ years

(Cl. D81—10)

FIG. 1

FIG. 2

FIG. 3

FIG. 4

FIG. 5

FIG. 6

FIG. 1 is a front perspective view of a hibachi showing my new design;

FIG. 2 is a top plan view thereof;

FIG. 3 is a rear elevation thereof; and

FIG. 4 is a bottom plan view thereof.

FIG. 5 is a top plan view of the hibachi with the cover removed, and

FIG. 6 is a cross-sectional view on the line 6—6 of FIG. 3 in the direction of the arrows.

I claim:

The ornamental design for a hibachi or similar article, substantially as shown.
